UNITED STATES PATENT OFFICE.

WILLIAM V. THRELFALL, OF NEWTON, MASSACHUSETTS, ASSIGNOR TO THE
PETTEE MACHINE WORKS, OF SAME PLACE.

MACHINE FOR DRAWING AND EVENING SLIVER.

SPECIFICATION forming part of Letters Patent No. 532,405, dated January 8, 1895.

Application filed February 17, 1894. Serial No. 500,511. (No model.)

To all whom it may concern:

Be it known that I, WILLIAM V. THRELFALL, a citizen of the United States, residing at Newton, in the county of Middlesex and State of Massachusetts, have invented a new and useful Improvement in Machines for Drawing and Evening Sliver, of which the following is a full, clear, and exact description, reference being had to the accompanying drawings forming a part of this specification, in explaining its nature.

The invention relates to that part of the machine for drawing and evening sliver which has to do with the drawing, calendering or smoothing of the sliver and its delivery to the receiving can. These devices, broadly speaking, include calendering or smoothing rolls which also act as feeding or drawing rolls and a rotary throat for laying the sliver in coils in the can, and heretofore they have been arranged in a way which has required a complex and somewhat expensive mechanism, as well as one which has not been entirely satisfactory in operation. This was caused by the supposed necessity for having two sets of rolls, one of which was stationary, and the other of which was either carried by the revolving throat or guide and required quite complicated devices to rotate, or was separated from the drawing rolls and located between the plates supporting them and the top of the revolving throat.

I have ascertained that the defects of the old organization can be overcome and the cost of the construction cheapened by dispensing with the use of the rolls heretofore carried by the revolving throat or immediately above it, and by using an additional roll in connection with the drawing rolls, so that in the smoothing, feeding and delivery of the sliver to the can, I use three non-traveling rolls instead of four located over a rotary throat without any rolls.

The invention relates to other features which will be hereinafter fully described, the same relating to a removable funnel and adjustable stops for regulating the extent of movement of the lever operated by the sliver in its passage through the funnel.

50 In the drawings, Figure 1 is a view in side

elevation of the part of the machine having the features of my invention. Fig. 2 is a view in vertical central section through the same. Fig. 3 is a view in plan of my improvement, and Fig. 4 is a view in side elevation showing the upper drawing roll and the guide roll as removed from the lower drawing roll. 55

The mechanism for drawing the sliver is, with the exception of its regulating lever, not shown.

A represents the upper part of the can which receives the sliver. It is rotated in the usual way. Above the can is the frame B which supports or carries the various devices constituting the present invention. It is 65 preferably made in the upper part b and lower part b' which are separable from each other, and the upper part has brackets b¹⁰ b² for supporting the drawing, calendering or smoothing and feeding rolls C, C', C². 70

The roll C is carried by the brackets b¹⁰ which are in the form of pillow blocks with removable caps. The rolls C' C² are represented as carried by a two-armed bracket which is hinged at b³ to the bracket b¹⁰ so that 75 both rolls can be swung upward and inward from the roll C, entirely clearing it and exposing it so that it may readily be examined, and, if necessary, removed.

The bracket, it will be understood, has two 80 arms parallel with each other and the bearings for the roll C' are at b⁴ and the caps b⁴ are removable. The roll C² has the open bearings b⁵ by which it may be removed from the bracket without removing caps or disturbing 85 the position of the bracket.

The rolls C C' are positively driven, that is, on each roll shaft there is a gear which meshes with the gear of the other shaft. The roll C² is driven by friction of the roll C thereon. 90 The shaft of the roll C is driven in the ordinary way and the rolls are located in relation to each other as shown in Figs. 1 and 2, the roll C² being when in operative position substantially upon the same plane as that of the roll C, and the roll C' being a little removed forward from a position directly over the center of the roll C. This enables the rolls to draw and smooth the sliver and at the same time to turn its direction and feed it down- 95 100

ward through the throat, the rolls C, C' acting as the drawing and smoothing rolls and the rolls C C² acting as the smoothing rolls and as directing and feeding rolls in addition.

- 5 The funnel D is like that ordinarily used in this class of machine and performs the same function. Instead, however, of being made integral with the lever d, as in the old type of machine, it is made separate from the 10 lever and detachable or removable therefrom, the lever having at its upper end an enlargement d', in which there is a hole d², and the funnel D is made with the circular section d³ to fit the hole and the shoulder d⁴, and it is held in place in the hole by the locking screw d⁵. This construction is advantageous in that it is necessary to change the funnel from time to time to vary the size of the feed hole d⁶ through which the sliver passes, it being understood that this is a very delicate part of the machine, as the sliver as it is drawn through this hole must serve to 20 actuate the lever d in the operation of evening the sliver, and the hole, therefore, must not be too 25 large or too small for the sliver being worked upon, and the hole must also be close to the nipping or drawing points or sections of the rolls C, C'. As the staple of the cotton varies in length, it is possible to vary the distance of 30 this hole from the meeting sections of the rolls a limited distance. Heretofore, there has been, so far as I am aware, no means for readily changing this position, the position of the lever and funnel being established by a fixed 35 stop which had to be filed or added to in order to change the distance inward or outward. I accomplish this change in position by means of adjustable stops d⁷ d⁸, and especially by the stop d⁷. They are each represented in the form of headed screws, one 40 screwing in the post d⁹ and the other in the post d¹⁰, and each has a check nut for holding the stop in its adjusted position. It is apparent that these stops d⁷, d⁸ can be adjusted 45 so as to limit the movements of the lever d in either direction as it vibrates under the passage of the sliver through the funnel or trumpet D.

The sliver is passed from the rolls C C² 50 through the throat E to the can. This throat extends diagonally in the throat forming block or piece e from its upper opening or inlet e' to the outlet e². The inlet is centrally located in relation to the two rolls C C². The 55 outlet is sufficiently out of line with the inlet to cause the sliver to be laid in the can in a coil. The block or part e in which the throat is, is integral with or carried by the rotary plate e³ which has a bearing at e⁴ upon the section b' of the frame, the said section having a large circular hole e⁵ to receive a portion of the plate e³. There is attached to the outer edge of the plate or formed thereon a gear e⁶ with which a rotating pinion engages, and the plate and throat are constantly turned and at the desired speed. The pinion

is rotated in the manner common to the old type of device.

The block e may have at its upper end a bearing at e⁷, there being a bearing or cover 70 plate e⁸ fastened to the part B and having a thin or narrow edge about the opening which receives the upper part of the block.

The operation of the device is as follows: The sliver passes through the evening rolls 75 and the funnel to the drawing and smoothing rolls C C', and the action of the evening rolls or devices is automatically controlled as in the old type of machine through the funnel and lever d. The rolls C C² turn the 80 sliver and serve to advance it or feed it downward through the throat E, and that, taken in connection with the drawing action upon the sliver caused by the rotation of the can serves to feed the sliver through the throat 85 and to lay it in the can in a suitable coil and without the necessity of auxiliary feeding devices.

The cover plate e⁸ is cut away upon its under side to permit the block e to be moved 90 downward therefrom with the part b' which is hinged at X to the part b. The roll C² is supported so that when in operative position it bears against the roll C.

I do not confine myself to the especial means 95 for supporting the rolls C' C² in relation to the roll C herein specified, but may use any mechanical equivalent for the devices herein described for supporting them in operative relation thereto upon the section b.

The caps for the boxes of the roll C' are represented as connected by a curved connection or plate f, the under surface of which may be lined with flannel or other similar material and form a cleaning or clearing device for the roll C'. 105

Having thus fully described my invention, I claim and desire to secure by Letters Patent of the United States—

1. In a machine of the character specified, 110 the combination with a positively driven drawing roll mounted in fixed bearings on the machine frame, of a swinging bracket hinged to the main frame, a second positively driven drawing roll mounted in said swinging 115 bracket, and a guide roll also journaled in said swinging bracket, substantially as described.

2. In a machine of the character specified 120 the combination with a positively driven drawing roll mounted in fixed bearings on the frame, of a second positively driven drawing roll mounted in a swinging bracket above and slightly forward of said first named drawing roll and co-operating therewith, a guiding 125 roll also mounted in said swinging bracket, and a movable funnel in proximity to said drawing rolls.

3. In a machine of the class specified, the 130 combination with the positively driven drawing roll C, of the positively driven drawing roll C' mounted in a swinging bracket hinged

to the main frame, and the guide roll C² also journaled in said bracket and bearing against the drawing roll C, substantially as described.

5. 4. In a machine of the class specified, the combination with the positively driven drawing rolls C C', one of which is mounted in fixed bearings on the frame of the machine and the other of which is journaled in a swinging bracket provided with open bearings, of the guide roll C² mounted in said open bearings in the said swinging bracket, substantially as described.

5. In a machine of the class specified, the combination with the positively driven draw-

ing rolls C, C', the former (C) of said rolls being mounted in fixed bearings on the main frame, of a swinging bracket in which the latter (C') of said rolls is mounted, the lever d pivoted on the main frame and provided at its upper end with a circular aperture, the funnel D having the shoulder d⁴ mounted in said aperture, the holding screw d⁵, and the adjustable stops d⁷, d⁸, on either side of the said lever, substantially as described. 20

WILLIAM V. THRELFALL.

In presence of—

F. F. RAYMOND, 2d,
J. M. DOLAN.
